JOSEPH L. GAIRE, OF PATERSON, NEW JERSEY

HAIR WAVING APPARATUS

Application filed October 8, 1930. Serial No. 487,296.

This invention relates to hair waving equipment and more particularly to devices for producing so-called permanent waves in human hair.

The primary object of the invention is to provide an efficient hair waving or curling device by which the hair may be permanently curled or waved without danger to the hair or scalp of the subject, the device being so constructed, arranged and adapted to operate that it may be conveniently employed with standard croquinole machines.

Another object of the invention is to provide an apparatus of the above character in which the flannel pads usually employed for protecting the head are omitted, thus materially reducing the cost of producing a permanent wave.

Still another object of the invention is to construct the permanent waving device so that the same may be efficiently employed with either live steam apparatus or electrical heating units of standard form.

Yet another object of the invention is to provide a permanent hair waving device which will enable the operator to soak the hair considerably more than has been possible with devices or systems heretofore in use, the steam being concentrated within the device and permitted to escape very slowly, thus enabling the device to produce a vapor permanent natural wave in which the waves will be soft and deep, while also eliminating the danger of steam burns on the scalp of the subject.

Other objects are to provide an improved type of hair strand clamp and to simplify and improve the construction of the clamp and steaming apparatus, whereby the number of parts required will be materially reduced and the employment of the device will be materially simplified due to the facility with which the same may be applied to the hair.

Another object of the invention is to enable a strand of hair to be curled to be clamped in the form of a flat band relatively close to the scalp, the clamping means being adapted to insulate the steam curling chamber from the subject's head.

A further object of the invention is to enable the hair strands to be wound laterally upon the curling members so that the curling or waving is produced upon the strand to a point close to the scalp, thereby producing 55 a more thorough and complete wave formation, and enhancing the effect of the permanent wave.

A still further object is to enable the steam to be confined in the curling or steam chamber, the side portion through which the base of the strand extends being sealed against escape of steam in proximity to the scalp, an orifice or the like being provided to permit exhaust steam to escape in an upward 60 or outward direction away from the scalp, so that the subject may not be rendered uncomfortable during the steaming operation.

Other objects and advantages of the invention will be hereinafter specifically pointed out, or will become apparent, as the specification proceeds.

With the above indicated objects in view, the invention resides in certain novel constructions and combinations, and arrangement of parts, clearly described in the following specification and fully illustrated in the accompanying drawings, which latter shows embodiments of the invention as at present preferred.

In the drawings:

Fig. 1 is a perspective view illustrating the device in use;

Fig. 2 is a top plan view of the shell;

Fig. 3 is a longitudinal sectional view of 85 the shell taken on the line 3-3 of Fig. 2, looking in the direction of the arrows;

Fig. 4 is a transverse sectional view through the shell, taken on the line 4-4 of Fig. 3;

Fig. 5 is a detail view of one end of the hair strand clamp; and

Fig. 6 is a transverse section through the hair strand clamp, substantially on the line 95 6-6 of Fig. 5.

In the form of my present device as shown in the accompanying drawings, the lock or strand of hair 10 is separated and securely held in the form of a flat band within a clamp 11 which includes a pair of elongated 105

members 12 and 13 pivotally connected to each other at one end, as seen at 14.

The clamp members 12 and 13 in this instance are preferably formed of relatively light but durable material, such as thin bars of aluminum. The member 12 is preferably doubled upon itself in flat U-shape; and the member 13 has an upstanding leg 15 which is received between the arms of the U-shaped member 12 to provide a pivot 16 for the two clamp members.

Means are provided to clamp the members 12 and 13 together; and for this purpose the end of the member 12 opposite to the hinge pivot 16 has a flat spring latch member 17 secured between the arms of the U of said member 12. This latch member 17 has an offset portion 18 carrying a hook 19 which latter is adapted to engage the lower edge of the member 13 when the clamping members are secured together.

Resilient means are provided to secure a tight, locking engagement between the clamping members 12 and 13. In this instance the members 12 and 13 are provided with coverings 20 and 21 respectively which may desirably be of rubber.

Means are also provided to protect the scalp of the subject during the steaming operation, and for this purpose one side of each of the clamping members has a pad 22 and 23, respectively, suitably secured to the resilient coverings 20 and 21, as by being vulcanized thereto, or by stitching, or otherwise. The pads 22 and 23 preferably extend the full length of the clamping members; and these pads may be formed of one or a plurality of layers of flannel or other material of low heat conductivity.

The relation between the clamping members is such that when the clamp is open the locking ends of the members 12 and 13 are slightly offset from each other in a vertical plane. When the hair strand is clamped in place the members 12 and 13 are moved into parallel relationship as the hook 19 is applied to the member 13. When the clamp is to be opened, a slight pressure upon the clamping members in their closing direction causes the hook 19 to be released as the locking ends of the members spring away from each other to a position slightly out of parallel as above referred to, this movement being accomplished by but one hand of the operator.

To form the curls or waves in the hair preliminary to the steaming operation, I provide in this instance a hollow tubular curling rod 24 having an elongated clamp 25 pivoted thereto. One end of the curling rod 24 is preferably closed, as seen at 26 and the opposite end is open as indicated at 27, the opening 27 being normally closed by a removable plug 28. The free end of the hair strand 10 is secured beneath the clamp 25, and the curl-

ing rod 25 is then rotated to wind the hair strand upon the surface of the rod 24.

The tubular curling rod 24 with its wound hair strand is brought relatively close to the hair strand clamp 11. A cylindrical housing 29, having a closed end 30, an open end 31 and a slot 32 extending to the open end 31, is then placed over the curling rod, the portion of the hair strand 10 between the clamp and the curling rod being received in the slot 32. The end of the tubular curling rod 24 adjacent to the plug 28 is provided with a gasket 33 which affords a tight fit for the curling rod within the cylindrical housing 29.

An elongated clamping member 34, having a lining 35, in this instance of rubber is provided for closing the slot 31. This clamping member 34 has a ring portion 36 integral with one of its ends; and this ring portion is adapted to surround one end of the cylindrical housing 29, while the opposite end of the clamping member 34 is secured in place by means of a loose ring 37.

In the operation of the device the hair strand is first thoroughly soaked with water or other suitable liquid solution, and the parts of the device are then assembled in the manner already described. A suitable portable electric heating device 38 indicated in dotted lines in Fig. 1, is then clamped about the cylindrical casing 29, and the electric current is then applied. The tubular curling rod 24 is provided with a plurality of apertures 39 about its wall so that the steam generated within the cylindrical housing thoroughly permeates the wound hair strand. It is understood of course, that when so used, the plug 28 is in its place, closing the opening 27 of the curling rod. A small orifice 40 is provided in the wall of the cylindrical housing 29, so that the steam may escape only very slowly. The hair is thus heated to a point of gentle steaming without any dry heat coming in contact with the hair.

When it is desired to employ live steam supplied from a suitable steam generator, instead of the electric heating element 38, the plug 28 is removed and a suitable tube leading from the steam generator is inserted within the opening 27.

Considerable particularities of description, as to materials, part details, dimensions, capacities and utilities may have been herein indulged in, but it will be understood that these statements, made with particular reference to that one, and the one now preferred, of the many possible embodiments of the invention which is illustrated in the drawings, are not in any way to be taken as definitive or limitative of the invention. Inasmuch as many changes could be made in the above constructions, and many apparently widely different embodiments of the invention could be made without departing from the scope

thereof, it is intended that all matter contained in the above description or shown in the accompanying drawings shall be interpreted as illustrative and not in a limiting sense.

5 It is also to be understood that the language contained in the following claims is intended to cover all the generic and specific features of the invention herein described, 10 and all statements of the scope of the invention which, as a matter of language, might be said to fall therebetween.

In other words, the scope of protection contemplated is to be taken solely from the 15 appended claims, interpreted as broadly as is consistent with the prior art.

What I claim as new is:

1. A permanent hair waving equipment including, in combination, a hair strand clamp 20 adapted to separate a strand of hair in proximity to the scalp of the subject, a hollow curling rod adapted to receive a hair strand wound thereon, said curling rod having an open end, a removable plug for said open end 25 of said curling rod, a housing for said curling rod, said housing having a closed end, an open end and a slot extending to said open end, said slot adapted to receive an unwound portion of said hair strand, a clamping member 30 for closing said slot, means for securing said clamping member in place over said slot, said housing having a steam outlet orifice, and means for steaming the hair strand wound upon said curling rod.

55 2. A permanent hair waving equipment including, in combination a hair strand clamp adapted to separate a strand of hair in proximity to the scalp of the subject, a hollow tubular curling rod adapted to clamp the free end of said hair strand and upon which curling rod the hair strand is adapted to be wound, said curling rod having an open and a closed end and a plurality of body perforations, a removable plug for the open end of 40 said curling rod, a cylindrical housing for said curling rod, said housing having a closed end, an open end and a slot extending to said open end, said slot adapted to receive an unwound portion of said hair strand, a clamping member 45 for closing said slot, said clamping member having a portion integral with one of its ends, adapted to surround said housing, a removable clamping device for the opposite end of said clamping member, 50 said housing having a steam outlet orifice, and means for steaming the hair strand wound upon said curling rod.

55 3. A permanent hair waving equipment including, in combination, a hair strand clamp 60 adapted to separate a strand of hair in proximity to the scalp of the subject, a curling rod upon which the hair strand is adapted to be wound, said curling rod having an open and a closed end and a plurality of body perforations, a removable plug for the open

end of said curling rod, a housing for said curling rod, said housing having a closed end, an open end and a slot extending to said open end, said slot adapted to receive an unwound portion of said hair strand, a clamping member 70 having a portion integral with one of its ends, adapted to surround said housing, and a removable clamping member for the opposite end of said elongated clamping member.

4. A permanent hair waving equipment including, in combination, a hair strand clamp 75 adapted to separate a strand of hair in proximity to the scalp of the subject, a hollow tubular curling rod adapted to clamp the free end of said hair strand and upon which curling rod the hair strand is adapted to be wound, said curling rod having an open and a closed end and a plurality of body perforations, a removable plug for the open end of 80 said curling rod, a cylindrical housing for said curling rod, said housing having a closed end, an open end and a slot extending to said open end, said slot adapted to receive an unwound portion of said hair strand, packing means on said curling rod, at the open end of said housing, an elongated clamping member for closing said slot, said elongated clamping member having integral means at one of its ends and removable means at the 85 opposite end to secure said elongated clamping member in place over the slot of said housing, and means for steaming the hair strand wound upon said curling rod.

5. A permanent hair waving equipment including, in combination a hair strand clamp 90 adapted to separate a strand of hair in proximity to the scalp of the subject, a hollow tubular curling rod adapted to clamp the free end of said hair strand and upon which curling rod the hair strand is adapted to be wound, said curling rod having an open and a closed end and a plurality of body perforations, a removable plug for the open end of 95 said curling rod, a cylindrical housing for said curling rod, said housing having a closed end, an open end and a slot extending to said open end, said slot adapted to receive an unwound portion of said hair strand, packing means on said curling rod, at the open end of said housing, an elongated clamping member for closing said slot, said elongated clamping member having a circular portion integral with one of its ends, said circular portion adapted to surround said housing, a removable clamping ring for the opposite end of 100 said elongated clamping member, said housing having a steam outlet orifice, and means for steaming the hair strand wound upon said curling rod.

6. A permanent hair waving equipment 105 including, in combination, a hair strand clamp adapted to separate a strand of hair in proximity to the scalp of the subject, a curling rod adapted to receive a hair strand wound thereon, a housing for said curling 110

rod, said housing having a closed end, an open end and a slot extending to said open end, said slot adapted to receive an unwound portion of said hair strand, a clamping member for closing said slot, means for securing said clamping member in place over said slot, said housing having a steam outlet orifice, and means for steaming the hair strand wound upon said curling rod.

7. A permanent hair waving equipment including, in combination, a hair strand clamp adapted to separate a strand of hair in proximity to the scalp of the subject, a curling rod adapted to clamp the free end of said hair strand and upon which curling rod the hair strand is adapted to be wound, a cylindrical housing for said curling rod, said housing having a closed end, an open end and a slot extending to said open end, said slot adapted to receive an unwound portion of said hair strand, a clamping member for closing said slot, said clamping member having a portion integral with one of its ends, adapted to surround said housing, a removable clamping device for the opposite end of said clamping member, said housing having a steam outlet orifice, and means for steaming the hair strand wound upon said curling rod.

8. A permanent hair waving equipment including, in combination, a hair strand clamp adapted to separate a strand of hair in proximity to the scalp of the subject, a curling rod upon which the hair strand is adapted to be wound, a housing for said curling rod, said housing having a closed end, an open end and a slot extending to said open end, said slot adapted to receive an unwound portion of said hair strand, a clamping member having a portion integral with one of its ends, adapted to surround said housing, and a removable clamping member for the opposite end of said elongated clamping member.

In testimony whereof I hereby affix my signature.

JOSEPH L. GAIRE.
